UNITED STATES PATENT OFFICE.

CHARLES KUBACH, OF ABILENE, KANSAS.

MULTIPLE MOLD FOR FENCE-POSTS.

No. 899,416.

Specification of Letters Patent.

Patented Sept. 22, 1908.

Application filed August 17, 1907. Serial No. 389,026.

To all whom it may concern:

Be it known that I, CHARLES KUBACH, a citizen of the United States, residing at Abilene, in the county of Dickinson and State of 5 Kansas, have invented new and useful Improvements in Multiple Molds for Fence-Posts, of which the following is a specification.

My invention relates to multiple molds for 10 making fence posts from concrete or other plastic material.

The object of the present invention is the provision of a simple and inexpensive mold which can be readily set up by a farmer or 15 any person on the spot where it is desired to use the fence posts and utilized for molding simultaneously a number of posts.

Another object of the invention is the provision of a multiple mold for concrete fence 20 posts which will be constructed in a novel manner from boards, whereby provision is made to compensate for swelling of the boards by wet concrete and bulging from pressure of the concrete, which will be adapted to be readily assembled or taken apart without requiring experience on the part of 25 the user.

The invention contemplates the provision 30 of a plurality of base boards disposed in separated arrangement to permit swelling without buckling, end boards associated with the base boards in an improved fashion, outside braces on the outer base boards, and partition boards held in an improved manner, together with other novel features, all of which 35 are set forth fully hereinafter and recited in the appended claims.

In the accompanying drawings:—Figure 1 is a plan view showing the mold as it would 40 lie on the ground or on any suitable support; Fig. 2 is a longitudinal section on line 2—2 of Fig. 1; and Fig. 3 is a cross-section on line 3—3 of Fig. 1.

The base boards 1 are separated throughout 45 their length at their juxtaposed edges by spaces 2, which permit swelling of the base boards without causing them to buckle. Secured to the base boards by fastenings 3, are strips 4, which form the chamfer or bevel on one side of the post and they also constitute 50 braces for the partition boards 5, which are entirely separate from the base boards and are themselves provided with strips 6 secured at 7, which form the chamfers or bevels on the upper side of the posts being molded. Owing to the small scale of the drawing, the

strips 4 are shown in close contact with the partition boards, but in practice they fit loosely together, enough play being left between them to permit the swelling of the 60 base boards and partition boards should they absorb moisture from the wet concrete. At the ends of the mold are end boards 8 and 9, which are provided with mortises 10 that receive the ends of the partition boards 5, 65 thereby locking said partition boards against lateral movement. The end boards 8 and 9 rest upon the base boards 1. End board 8 is provided with depending ends 11, which overhang and engage the outermost base 70 boards 1 (Fig. 3) to prevent the base boards from moving outwardly and separating, and the end board 9 is also constructed with overhanging parts 12 which correspond precisely to the overhanging parts 11 (Fig. 2) 75 and serve the same purpose.

The outer base boards 1 are considerably wider than the intermediate base boards to permit this engagement of the parts 11 and 12 and also to afford ledges to which are fastened abutment or bracing blocks 13 (Fig. 1) which prevent outward bulging of the outer partition boards on account of pressure of the concrete.

Hooks 14 are adapted for detachably connecting the outer partition boards 5 with the end boards 8 and 9 and they lock the entire mold together.

In setting up the mold, the base boards 1 are first laid down. The partition boards 90 are then inserted between the strips 4 and the end boards 8 and 9 are then placed in position, the mortises receiving the ends of the partition boards 5, and the hooks 14 are engaged with their eyes. The mold is then securely locked together. When the molds are filled with concrete, they are smoothed off and at the proper time the hooks are released and the mold taken apart and the posts removed and the molds are ready for 100 immediate subsequent use if desired.

Having thus described my invention, what I claim as new and desire to secure by Letters Patent, is:

1. A multiple mold for fence posts, comprising base boards, abutment blocks on the outermost base boards, partition boards, end boards having extremities which overhang the base boards and engage with them, and means for securing the base boards, partition 105 boards, and end boards in their respective 110 positions.

2. A multiple mold for concrete fence posts, comprising base boards which are separated at their juxtaposed edges to compensate for swelling of said boards, abutment blocks on the outermost base boards, partition boards, end boards, engaging with said base boards, and means for securing the base boards, partition boards, and end boards in their respective positions.
- 10 3. A multiple mold for fence posts comprising base boards, abutment blocks on the outermost base boards, strips secured to the edges of said base boards, partition boards fitting between said strips and themselves

provided with similar strips along their upper edges, an end board for the bases of the posts having extremities which overhang the base boards and engage them, an end board for the tops of the posts, and means for securing the base boards, end boards and partition boards in their respective positions.

In testimony whereof I have signed my name to this specification in the presence of two subscribing witnesses.

CHARLES KUBACH.
